UNITED STATES PATENT OFFICE

101,858

DESIGN FOR A CASING FOR A SUCTION CLEANER OR SIMILAR ARTICLE

Henry Dreyfuss, New York, N. Y., assignor to The
Hoover Company, North Canton, Ohio, a cor-
poration of Ohio

Application October 7, 1935, Serial No. 58,861

Term of patent 14 years

To all whom it may concern:

Be it known that I, Henry Dreyfuss, a citizen
of the United States, residing at New York city,
in the county of New York and State of New
York, have invented a new, original, and orna-
mental Design for a Casing for a Suction Cleaner
or Similar Article, of which the following is a
specification, reference being had to the accom-
panying drawing forming a part thereof.

The band extending around the motor casing
at a lower level than the headlight opening
therein, and the circular disc upon the top of the
motor casing, are important features in the pres-
ent design.

In the drawing:

Figure 1 is a top view of the casing for a suc-
tion cleaner or similar article, showing my new
design;

Figure 2 is a view in perspective of the casing;
and

Figure 3 is a front elevation of the same.

I claim:

The ornamental design for a casing for a suc-
tion cleaner or similar article, as shown and de-
scribed.

HENRY DREYFUSS.
